UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A HOLDER FOR LAMP-FOUNTS.

SPECIFICATION forming part of Design No. 24,130, dated March 19, 1895.

Application filed February 18, 1895. Serial No. 538,906. Term of patent 3½ years.

To all whom it may concern:

Be it known that I, ALBERT PATITZ, of Meriden, in the county of New Haven and State of Connecticut, have invented a new Design for 5 a Lamp-Fount Holder, (Case C;) and I do hereby declare the following, when taken in connection with the accompanying drawings and the letters of reference marked thereon, to be a full, clear, and exact description of the same, 10 and which said drawings constitute part of this specification, and represent, in—

Figure 1, a side view of a lamp-fount holder embodying my design; Fig. 2, an outline top view of the same.

15 This invention relates to a design for a lamp-fount holder, and the design consists in the configuration and ornamentation as shown in the accompanying illustrations.

In general outline the fount-holder is bowl- 20 shaped. Springing from the lower edge of the holder is a series of conventionalized elongated

acanthus leaves A, curving gracefully outward and then inward, alternating with a simple scroll B, following the same general outline. From the contracted upper edge C 25 of the holder a series of ornamented reverse scrolls D extends upward and slightly outward, forming the upper configuration of the fount-holder, all as shown in the accompanying illustrations.

30 I claim—

The design for a lamp-fount holder as herein described and shown in the accompanying illustrations.

In testimony whereof I have signed this 35 specification in the presence of two subscribing witnesses.

ALBERT PATITZ.
